TORSION SPRING DEVICES

Max Ruegg, Detroit, and Von D. Polhemus, Franklin, Mich., assignors to General Motors Corporation, Detroit, Mich., a corporation of Delaware

Application March 21, 1952, Serial No. 277,881

2 Claims. (Cl. 267—57)

The present invention relates to torsion type springs and more particularly to means for improving the fatigue resistance of bars or rods which are subjected to torsional stresses.

Compared with other forms of springs, the torsion bar type of spring offers a very considerable advantage in ease of fabrication, low cost, simplicity and maintenance. Theoretically, all that is required to utilize the spring characteristics of a given length of bar is to anchor one end thereof and to provide a lever at the other end to apply torque. Such spring could be manufactured at relatively low cost if bars of uniform thickness throughout the length thereof could be utilized. It has been found, however, that torsion bars of uniform cross section have had a tendency to fracture prematurely, usually in the area where the bar emerges from the anchor or lever bracket. This tendency is particularly pronounced when the bars have been serrated or splined at each end and press fitted into the bores of the anchor and lever brackets. In experimenting with such constructions it has been found that the stress concentration produced by serrating is localized at the point of run-out of the serrations and that this further increases the tendency to fracture prematurely.

In the past attempts have been made to improve the fatigue resistance characteristic of bars by upsetting or otherwise enlarging the ends of the bar in order to provide a greater cross-sectional area at the point of stress concentration. This method of manufacture has tended to increase the life of spring somewhat and is used to some extent commercially. Torsion bars constructed by this method have not proven to be entirely satisfactory because of the relatively high cost of manufacture as compared with other types of structures, and the rate of production is also relatively low because of the forging operations required thereon.

It is an object of the present invention to provide a torsion bar of uniform cross section which offers greatly improved resistance to fatigue at the points of stress concentration.

Another object is to provide a torsion bar of uniform cross section which is highly resistant to fatigue, and which is adaptable to any of the common methods of attachment to the associated members.

A further object is to provide a torsion bar which is susceptible to extremely high speed fabrication and unusually low cost.

A still further object is to provide a torsion bar type of spring which is extremely simple in construction and highly efficient and durable in operation.

Other objects and novel features of the invention will appear more fully hereinafter from the following detailed description when taken in connection with the accompanying drawings illustrating several forms of the invention of which:

Fig. 1 is a side elevation, partly in section, of a torsion bar sleeved in an anchor block and lever arm, showing the serrated or knurled ends terminating in a reduced

2

portion which is substantially flush with the inner faces of the anchor block and lever arm.

Fig. 2 is an enlarged sectional view taken substantially along line 2—2 of Fig. 1 and of Fig. 1 showing one form of knurling employed.

Fig. 3 is a view similar to Fig. 1 in which the recesses formed in the torsion bar are disposed respectively, intermediate the ends of the mounting bracket and lever arm.

Fig. 4 is a view similar to Fig. 3 showing a modified construction wherein a second reduced portion at each end is substantially aligned with the inner faces of the respective anchor block and lever arm.

Fig. 5 is a view similar to Fig. 1 showing another modified construction wherein the ends of the bar are smooth and are secured against rotary movement in the anchor block and in the lever arm by threaded means.

Fig. 6 is a fragmentary side elevational view partly in section, showing a still further modification wherein the bar is of square cross section having a circular groove disposed near the inner face of the support therefor.

Fig. 7 is a sectional view of the bar shown in Fig. 6, the section being taken in a plane passing through the annular groove in the bar.

Fig. 8 is a view similar to Fig. 6 showing a still further modification wherein a torsion bar of polygonal construction is employed, and

Fig. 9 is a sectional end view of the bar shown in Fig. 8 taken through the plane of the circular groove provided therein.

Referring now to the drawings the numeral 2 designates a torsion bar secured at one end 4 in an anchor bracket 12 and at the other end 6 in a lever bracket 14. Both ends 4 and 6 of bar 2 are provided with longitudinally extending knurled portions 16 which may be formed thereon by a thread-rolling machine or other suitable device. In Fig. 2 the cross sectional form of the knurls 16 is illustrated on an enlarged scale. The anchor bracket 12 and lever bracket 14 are provided with bored apertures 8 and 10 respectively, into which the knurled end portions 16 of bar 2 are pressed. Apertures 8 and 10 are usually bored to a diameter slightly less than the pitch diameter of the knurled end portions 16 of the bar, in order to obtain an interlock of ample torque capacity. To secure a more favorable distribution of stresses in accordance with the invention, tapered annular grooves 32 are formed on the bar 2 at the run-out of the longitudinally extending knurled portions 16 and the bar 2 is pressed into the bored apertures 8 and 10 of the anchor and lever brackets 12 and 14 a sufficient depth to position the annular grooves 32 substantially flush with the inner faces 34 and 36 respectively, of the said anchor and lever brackets. Tests have shown that by disposing the annular grooves 32 in this manner a substantial reduction in stress concentration is obtained, thereby increasing the bar life by more than fifty percent. In addition to stress concentration where the bar 2 emerges from the brackets 12 and 14, it has been found that knurling or otherwise deforming the ends of the bar induces additional stress concentration which is localized at the run out of such knurling. It will therefore be apparent that in Fig. 1 the annular grooves 32 are formed on the bar 2 and positioned with respect the anchor and lever brackets 12 and 14 in such a manner as to relieve inherent stress concentrations occasioned by the rigid attachment of the bar to the brackets as well as stresses induced by knurling the end of the said bar.

A modification of the structure shown in Fig. 1 is illustrated in Fig. 3. In this construction a bar 2 has provided at the opposite ends 4 and 6 thereof a relatively short longitudinally extending knurled portion 16 and an

annular groove 32 at the run-out of each of said knurled portions. The opposite ends 4 and 6 of bar 2 are pressed into the anchor bracket 12 and lever bracket 14 a sufficient distance to place the annular grooves 32 in a plane intermediate the inner and outer faces 34 and 35 of said anchor bracket and the inner and outer faces 36 and 37 of lever bracket 14. Tests have shown that the bored apertures 8 and 10 of the anchor and lever brackets 12 and 14 overlap and grip the smooth portions 38 of the bar 2 ahead of the annular grooves 32 and tend to relieve the grooved portions 32 of the full torque load, thereby further improving the distribution of stresses and materially improving the bar life.

Fig. 4 shows a still further modification of the structure shown in Fig. 1. In this construction also the anchor bracket 12 and lever bracket 14 are pressed on the ends 4 and 6 of the bar 2. Each end 4 and 6 of the bar 2 shown in Fig. 4 is provided with short knurled end portions 16 and a pair of spaced apart annular grooves 32 and 40. The grooves 32 are formed at the run-out of each of the knurls 16 and occupy a plane intermediate the inner and outer faces 34 and 35 of the anchor bracket and the inner and outer faces 36 and 37 of the lever brackets 14. The grooves 40 occupy planes substantially flush with the inner faces 34 and 36 of the anchor and lever brackets 12 and 14, respectively. In this modification the annular grooves 32 relieve stress concentration induced by knurling while the grooves 40, shown here in tapering form, tend to relieve excessive stresses occurring in the press-fit area of the smooth portions 39 of the bar 2 between the grooves 32 and 40.

Fig. 5 shows a still further modification comprising a torsion bar 2 of substantially uniform cross section throughout and having smooth substantially cylindrical end portions 4 and 6. The end portions 4 and 6 of bar 2 are press fitted into bored apertures 8 and 10 of the anchor and lever brackets 12 and 14, respectively, and held securely therein by threaded members 41. Near each end of the bar 2 there is provided an indentation 42 into which the tapered end 43 of the threaded member 41 is firmly seated to provide a rigid connection of ample torque capacity. Annular grooves 32 are formed on each end of the bar 2 inwardly of the indentations 42 and occupy a plane substantially flush with the inner faces 34 and 36 of the anchor and lever brackets 12 and 14, respectively. It will be apparent that the threaded members 41 provide for axial positioning of the annular grooves 32 with respect to the inner faces of the anchor and lever brackets 12 and 14, respectively, as well as providing a rigid interlock between the bar and the said anchor and lever brackets.

Figs. 6 and 7 show a still further modification. In this construction the numeral 44 designates an anchor bracket having a substantially square aperture 45 provided therein. A substantially square torsion bar 46 having a stress relieving annular groove 32 formed near one end is pressed into the aperture 45 to obtain rigid engagement between the bar 46 and the anchor 44. In this embodiment the groove 32 is positioned in a plane substantially flush with the inner face 42 of the anchor bracket 44. Since the end portion 30 of the bar 46 requires no alteration to provide for rigid engagement, it will be apparent that this embodiment will substantially reduce the cost of fabricating the bar. The opposite end of bar 2 may be of similar construction and fitted into a substantially square opening provided in a lever bracket (not shown). Tests on this type of bar have indicated that stress concentrations are substantially reduced by an annular groove 32 therein having a cross sectional diameter substantially equal to the minimum cross section of the bar, as shown particularly in Fig. 7.

Figs. 8 and 9 illustrate a modification of the structures shown in Figs. 6 and 7 in which a torsion bar 47 of poly-

gonal cross section is press fitted into an anchor bracket 48 having an aperture 49 of similar polygonal shape. A stress relieving annular groove 32 is formed on the bar 47 near one end thereof. The end 50 of the bar 47 is axially adjusted into the aperture 49 so that the groove 32 occupies a plane adjacent the inner face 51 of the anchor bracket 48 and is preferably of a cross sectional diameter equivalent to that of the minimum width of said bar as illustrated in Fig. 9. The other end of the bar 47 may be similarly constructed and press fitted into a polygonal opening in a lever bracket (not shown).

While the present invention is particularly suitable in conjunction with torsion bars of substantially uniform cross section, it is to be understood that the advantages are equally applicable to bars of varying cross section, and the several illustrations therefore are not intended as defining limits of the invention. It therefore is to be understood that it is intended to limit the invention only by the scope of the claims which follow.

We claim:

1. In a device of the class described, the combination of an anchor bracket, a lever bracket, said brackets having opposed faces, each of said brackets having a bore formed therein, a torsion spring member, said member having an elongated intermediate portion of circular cross section and terminal end portions of circular cross section, said end portions and said intermediate portion being equal in diameter, knurl means on said end portions, stress relieving means formed on said bar at the junctures of said intermediate portion and said knurl means, said last mentioned means comprising tapered annular grooves in said bar, said taper diverging toward said intermediate portion of said bar, said knurl means being press fitted into the bores of said anchor and lever bracket to position said grooves in external flush relation with the opposed faces of said brackets.

2. In a device of the class described, the combination of an anchor bracket and a lever bracket having opposed faces, each of said brackets having a bore formed therein, a torsion spring member, said member having an elongated intermediate portion of circular cross section and terminal end portions of circular cross section, said end portions and said intermediate portion being equal in diameter, means forming serrations on said end portions, said serrations being adapted for press fitted gripping engagement with said bores, stress relieving means formed on said bar at the junctures of said intermediate portion and said serrations, said last mentioned means comprising annular grooves in said bar, said grooves having one wall generally transverse to the axis of said bar and another wall inclined with respect to the axis of said bar, said end portions being press fitted into the bores of said anchor and lever bracket to position the transverse walls of said grooves in flush relation with the opposed faces of said brackets.
